UNITED STATES PATENT OFFICE.

JAMES W. BUCHANAN, OF ASHEVILLE, NORTH CAROLINA.

LIFE-PRESERVER SUIT.

1,062,435.

Specification of Letters Patent. Patented May 20, 1913.

Application filed September 13, 1912. Serial No. 720,212.

To all whom it may concern:

Be it known that I, JAMES W. BUCHANAN, a citizen of the United States, residing at Asheville, in the county of Buncombe and 5 State of North Carolina, have invented certain new and useful Improvements in Life-Preserver Suits; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to life preserver suits and has for its object to provide a suit to be worn by persons for the purpose of causing them to float indefinitely and to protect them from the cold in such manner that a person can remain in the water for a comparatively long period of time without injury and distress.

With this object in view the invention 25 consists in the novel construction of the life preserver suit.

Referring to the accompanying drawings: Figure 1 is a perspective view of the life preserver suit illustrating the same applied to a person. Fig. 2 is a fragmentary 30 sectional view of the upper front interior portion of the suit, and Fig. 3 is a vertical longitudinal sectional view taken through the suit.

Like numerals of reference indicate the 35 same parts throughout the several figures in which;

1 indicates the suit which comprises the body portion 2, leg portions 3, arm portions 40 4 and hood or head portion 5. The arm portions 4 are provided with hand portions 6 while the leg portions 3 are provided with feet 7 to which suitable weights 8 are secured in the manner as shown in Figs. 45 1 and 2.

As will appear from the drawings the entire suit is formed inseparable and is opened at the top as shown at 9 in Fig. 2, the hood 5 being inseparably attached to the 50 back of the suit and formed thereon as shown in Fig. 3 in such manner that a sufficient opening is provided at the top of the suit to allow a person to enter the suit in this manner as will be apparent from an 55 inspection of Fig. 3.

Around the body or waist portion of the

suit is provided an air chamber 10 surrounding the body of the wearer, said air chamber being formed between the outer waterproof layer 11 of the suit and the inner air 60 tight layer 12 in the manner as shown in Fig. 3, while the lower body portions and leg portions of the suit are provided between the outer layer and the inner layer with a suitable felt or cotton filling 13 so as 65 to add warmth to the suit and prevent the wearer from the effects of the cold water, it being understood that by reason of the weights 8 the person within the suit floats in an upright or vertical position, the water 70 line being at a point under the arm pits of the wearer in such manner that all the submerged portion of the wearer is protected against the cold water.

In the front portion of the suit and communicating with the air chamber 10 I provide a small air pump 14 and a vent 15 in such manner that the air chamber 10 can be quickly and easily filled with air and can be readily emptied at will. Consequently suits 75 80 constructed in accordance with this invention can be packed or stowed aboard the ship in a very compact and convenient manner.

On the interior of the upper body portion of the suit and above the air chamber 10 I provide a plurality of pockets 16 which are arranged on the inside of the suit and are not available from the outside in such manner that any eatables or drinkables carried in the suit pockets will be protected 85 against the water and can be used at will by the wearer, the whole being arranged in such manner that a sufficient quantity of food and drink can be carried in said pockets 90 95 16 to sustain the person for a sufficient period of time in order to reasonably insure his rescue.

As before stated the hood 5 is formed on the back portion of the suit while about the opening 9 at the top of the body portion I provide a draw string 17 so arranged as shown in the drawings as to draw the upper body portion and lower portion of the hood snugly about the neck of the wearer 100 in the manner as shown in Fig. 1; while I provide around the edge of the hood 5 a similar draw string so arranged that the hood can be drawn snugly around the head 105 of the wearer in such manner that only his 110 face is unprotected in the manner as illustrated in Fig. 1.

Having thus fully described the invention it is entirely evident from the foregoing description taken in connection with the accompanying drawings that a person can quickly enter the suit in the manner as described. After first providing himself with suitable food and drink in the pockets 16 the draw strings 17 and 18 are then drawn closely and snugly into position shown in Fig. 1 and the air chamber 10 is provided with air through the medium of the pump 14 after which the person is ready to take to the water, and by reason of the construction of the suit as hereinbefore described he will float in an easy upright position and be protected against the severity of the cold and at the same time be maintained in condition to endure the hardships of the water for a considerable period of time.

Having thus fully described the invention what I claim as new and desire to secure by Letters Patent of the United States is:—

A life preserver suit comprising body, arm and leg portions formed integrally and inseparable from one another, a hood portion formed on the back of the suit at the top thereof, the top portion of the suit being provided with an opening sufficiently large to allow ingress of a person to the suit, the said suit comprising an outer

water-proof layer and an inner air tight layer, the lower body portion and leg portions of the suit being provided with a cold resisting filling material, the central body portion of the suit between the two layers 35 providing an air chamber, an air pump connected to the said air chamber to inflate the same, a vent communicating with the said air chamber to deflate the same, the entire body portion of the suit being provided 40 with a plurality of pockets available from the inside of the suit, the upper body portion of the suit adjacent the hood portion being provided with a draw string to close the said opening and to cause the said suit 45 to snugly encompass the neck of the wearer, the outer portion of the hood being provided with a draw string to cause the said hood to snugly encompass the head of the wearer in such manner that the face alone is exposed, and a suitable weight arranged under each foot portion of the suit, substantially as described and for the purposes set forth.

In testimony whereof, I affix my signature, in presence of two witnesses.

JAMES W. BUCHANAN.
